US0D1022516S

(12) United States Design Patent (10) Patent No.: US D1,022,516 S
(45) Date of Patent:  Apr. 16, 2024

(54) CUP DISPENSER

(71) Applicant: Xiaojun Wang, Shenzhen (CN)

(72) Inventor: Xiaojun Wang, Shenzhen (CN)

() Term: 15 Years

(21) Appl. No.: 35/517,871

(22) Filed: Jun. 29, 2023

(80) Hague Agreement Data

Int. Filing Date: Jun. 29, 2023

Int. Reg. No.: DM/230262

Int. Reg. Date: Jun. 29, 2023

Int. Reg. Pub. Date: Jul. 21, 2023

(51) LOC (14) Cl. 07-99

(52) U.S. Cl.

USPC D6/516; D7/619.1

(58) Field of Classification Search

USPC D7/601, 602, 619.1, 619.2, 624.2;

D6/515, 516, 535

CPC A47F 1/04; A47F 1/06; A47F 1/065; A47F

1/085; A47G 23/02; A47G 23/0208;
